US0D1008231S

(12) **United States Design Patent** (10) **Patent No.:** **US D1,008,231 S**
(45) **Date of Patent:** **** Dec. 19, 2023**

(54) **WIRELESS HANDHELD MICROPHONE**

(71) Applicant: **FUJIAN EASTWEST LIFEWIT TECHNOLOGY CO., LTD**, Fuzhou (CN)

(72) Inventor: **Cheng Zhao**, Fuzhou (CN)

(73) Assignee: **FUJIAN EASTWEST LIFEWIT TECHNOLOGY CO., LTD**, Fuzhou (CN)

(**) Term: **15 Years**

(21) Appl. No.: **29/909,567**

(22) Filed: **Aug. 8, 2023**

(30) **Foreign Application Priority Data**

Jul. 7, 2023 (CN) 202330423642.2

(51) **LOC (14) Cl.** **14-01**

(52) **U.S. Cl.**

USPC **D14/225**

(57) **CLAIM**

The ornamental design for a wireless handheld microphone, as shown and described.

DESCRIPTION

FIG. 1 is a perspective view of a wireless handheld microphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the wireless handheld microphone that form no part of the claimed design.

1 Claim, 8 Drawing Sheets
